UNITED STATES PATENT OFFICE.

GEORGE WILLIAM MILLNER, OF CHARLOTTETOWN, PRINCE EDWARD ISLAND, CANADA.

CREAMING-CAN.

SPECIFICATION forming part of Letters Patent No. 321,744, dated July 7, 1885.

Application filed March 17, 1885. (Model.)

To all whom it may concern:

Be it known that I, GEORGE WILLIAM MILLNER, a citizen of Canada, residing at Charlottetown, in the county of Queens and Province of Prince Edward Island, have invented certain new and useful Improvements in Creaming-Cans; and I do hereby declare that the following is a full, clear, and exact description of the invention, which will enable others skilled in the art to which it appertains to make and use the same.

This invention is an improvement in devices for drawing cream from milk; and it consists in certain novel constructions and combinations of parts, as will be hereinafter described, and pointed out in the claims.

In the drawings, Figure 1 is a perspective view, partly broken away, of a can provided with my improvements. Fig. 2 is a detail view of the tube. Fig. 3 is a detail bottom plan view of the packing-box and the tube. Fig. 4 is a detached section on about line $x-x$, Fig. 1, and Fig. 5 is a plan view of the device, all of which will be described.

The can C has an opening, C', through its bottom, and is provided with a guide-loop, C², fixed to its side, and arranged above and in line with the opening C'. The can is also provided near its upper end with a hook, C³, on which to support the swinging end of the tube-handle when the cream is rising. To the under side of the can I fix the box D, formed with a cylindrical portion, d, and a base-flange, d'. The boxing is arranged around and below the opening C', and the plate d' has an opening, d'', coinciding with the opening C', as shown most clearly in Fig. 4. Into the box D, I spring the rubber or other suitable packing-ring, E, which has an opening, e, fitted to permit the passage of the tube B. By the described construction of packing-box, consisting of the box D and the ring E, the latter may be conveniently removed and replaced when the tube is withdrawn. This renders the construction easy of access for the purpose of cleansing and sunning, as is desirable in milk-vessels. The tube B is held and movable longitudinally through the guide C² and opening C'. The guide C² operates to retain the tube B in true position, so that the tube will not incline to one side or the other. This

inclination is objectionable, as it operates to force the tube away from the packing-ring on one side, and so permits the escape of milk. To the upper end of the tube B, I pivot one end of a handle, B', the other or swinging end of which is provided with a loop hand-hold, b, which may be supported on the hook C³, and so held from dropping into the milk, and is at the same time supported below the cover 60 of the can. By this handle the tube may be depressed or elevated, and its upper end set above or at any desired point below the surface of the contents of the can.

In operation the tube, which is open at both ends, is placed in the can in the position most clearly shown in Fig. 1, with its upper end arranged above the surface of the milk and cream. When the cream has formed, the tube may be depressed below the cream and the latter be withdrawn without affecting the milk, which latter may be drawn by a further depression of the tube.

Manifestly, the opening C' might be formed through the side instead of the bottom of the can; but I prefer to arrange it as shown and before described.

Having thus described my invention, what I claim, and desire to secure by Letters Patent, is—

1. The combination, with the can having an opening, C', and a hook, C³, fixed within said can near its upper end, of the tube movable longitudinally through the opening C', and a handle pivoted at one end to the tube, and having its other end supported on the hook C³, substantially as set forth.

2. The combination, substantially as herein set forth, of the can having an opening, C', a guide, C², secured in the can in line with opening C', a hook, C³, secured within and close to the top of the can, the tube movable longitudinally through guide C² and opening C', and handle B', pivoted at one end to the tube, and provided at its other end with a hand-hold, b, adapted to engage and be held by the hook C³, substantially as set forth.

GEORGE WILLIAM MILLNER.
